BRAKE BEAM FULCRUM

Armand H. Peycke, Kenilworth, Ill., assignor to
American Steel Foundries, Chicago, Ill., a cor-
poration of New Jersey

Application July 21, 1931, Serial No. 552,126

9 Claims. (Cl. 188—231)

This invention pertains to brake beam fulcrums, and more particularly to attachment or positioning means between a brake beam fulcrum and compression member of a brake beam assembly.

It is an object of this invention to provide a brake beam construction dispensing with the usual wedges and other separate parts usually employed for locking the fulcrum in fixed relation to the assembly.

Another object of the invention is to provide positioning means between a plurality of members, the positioning means being integral with certain of said members whereby extra parts are eliminated.

With these and various other objects in view, the invention may consist of certain novel features of construction and operation, as will be more fully described and particularly pointed out in the specification, drawing and claims appended hereto.

In the drawing, which illustrates an embodiment of the device and wherein like reference characters are used to designate like parts—

Figure 1 is a fragmentary sectional top plan view of one form of brake beam embodying the invention;

Figure 2 is a sectional elevation through the brake beam construction shown in Figure 1;

Figures 3 and 4 are fragmentary sectional elevations showing different forms of connection between the brake beam fulcrum and compression member.

Referring first of all more particularly to the form of device illustrated in Figures 1 and 2, the brake beam compression member 10 is shown of rectangular channel shape, the channeled portion facing the tension member 12. The brake beam fulcrum 14 is disposed between the tension and compression members forming a truss-like structure, the fulcrum including a channeled seat portion 16, the jaws of which embrace a portion of the tension member 12. The fulcrum is slotted as at 18 and provided with the spaced aligned apertures 20 for the reception of suitable supporting pin mechanism. The fulcrum adjacent the compression member 10 is provided with the head 22, the head being substantially of rectangular elevation as viewed in Figure 2 and being adapted to snugly embrace or extend around the compression member. The outside strap 24 of the head is provided with the inwardly extending dowel 26 adapted to be received in a suitable aperture 28 provided in the web 30 of the compression member. The ful-

crum member 14 is provided with the positioning fingers 32 adjacent the sides of the head 22, the fingers 32 being adapted to be bent from the dotted line position shown in Figure 1 to the full line position shown in Figure 1 wherein the fingers form positioning means to prevent relative movement between the fulcrum 14 and the compression member 10 so that the fingers 32, with the dowel 26, form effective locking means between the compression member and the fulcrum.

In Figure 3 the compression member 33 is shown having the legs 34 and 36 angularly disposed to form a V-shaped channel with respect to each other. The brake beam fulcrum 38 is provided with the head 40 having the straps 42 and 44 angularly disposed with respect to each other, and closely embracing the legs 34 and 36, the head being immovably positioned by means of the dowel 46 received in the aperture 48 and the spaced fingers 50 provided on the fulcrum being adapted to be bent in contact with the member 33.

In the construction shown in Figure 4, the compression member 52 is substantially of arcuate shape to form a round bottom channel, and the head 54 of the fulcrum 56 has the strap portion 58 corresponding to the arcuate compression member as before and being provided with the dowel 60 received in the aperture 62 in the compression member, the fulcrum having the fingers 64 provided adjacent the head 54 and adapted to be bent into locking engagement with the compression member.

With the forms of construction shown, it will be appreciated that a simple connection is provided, yet one which is very effective and rugged. There are no wedges or loose parts to be lost and the members are very easily associated or assembled, one with respect to the other, and it is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

1. A fulcrum member adapted to be assembled with a substantially channel-shaped beam member, said fulcrum member having a head adapted to receive and substantially embrace said beam member, said head having fingers on opposite sides thereof at the marginal edges of the opening of the head, said fingers normally being inclined from said head to permit assembly of said mem- 55

bers and being adapted to be bent toward said beam member to engage said beam member to secure said members together.

2. In a brake beam, the combination of a channel-shaped beam member, a fulcrum member having a head adapted to receive said beam member, said head having spaced fingers at the sides thereof extending to engage said beam member to secure said members together.
3. In a brake beam, the combination of a channel-shaped beam member, a fulcrum member having a head adapted to receive said beam member, said head having spaced fingers on the outside thereof extending to engage said beam member to secure said members together.
4. In a brake beam, the combination of a channel-shaped beam member, a fulcrum member having a part adapted to receive said beam member, said fulcrum member having spaced fingers on the outside thereof extending to engage said beam member to secure said members together.
5. In a brake beam, the combination of a channel-shaped beam member, a fulcrum member having a part adapted to receive said beam member, said part being provided with a dowel received in an aperture of said beam member for positioning said members, said fulcrum member having spaced fingers on the outside thereof extending to engage said beam member to secure said members together.
6. In a brake beam, the combination of a V-

shaped beam member, a fulcrum member having a part adapted to receive said beam member, said fulcrum member having spaced fingers on the outside thereof extending to engage said beam member substantially at the junction of the legs thereof to secure said members together.

7. In a brake beam, the combination of a V-shaped beam member, a fulcrum member having a part adapted to receive said beam member, said part being provided with a dowel received in an aperture of said beam member for positioning said members, said fulcrum member having spaced fingers on the outside thereof extending to engage said beam member substantially at the junction of the legs thereof to secure said members together.

8. In a brake beam, the combination of a round bottom beam member, a fulcrum member having a part adapted to receive said beam member, said fulcrum member having spaced fingers on the outside thereof extending to engage said beam member to secure said members together.

9. In a brake beam, the combination of a round bottom beam member, a fulcrum member having a part adapted to receive said beam member, said part being provided with a dowel received in an aperture of said beam member for positioning said members, said fulcrum member having spaced fingers on the outside thereof extending to engage said beam member to secure said members together.

ARMAND H. PEYCKE.
